UNITED STATES PATENT OFFICE.

LOUIS A. HOERR, OF ST. LOUIS, MISSOURI.

CARLINE.

1,229,267.

Specification of Letters Patent. Patented June 12, 1917.

Application filed February 15, 1915. Serial No. 8,226.

To all whom it may concern:

Be it known that I, LOUIS A. HOERR, a citizen of the United States of America, residing at the city of St. Louis, State of Missouri, have invented a certain new and useful Carline, of which the following is such a full, clear, and exact description as will enable any one skilled in the art to which it appertains to make and use the same, reference being had to the accompanying drawings, forming part of this specification.

My invention relates to a carline and has for its object the production of a carline which will be provided with a sufficiently large seat for the ridge pole and which will be adapted to support a ridge pole which is not in alinement with the underfaces of the purlins, and, which will, further, enable the carline to be secured to the ridge pole without weakening the truss beam of the carline. Still another object of my invention is to provide improved means for securing the ends of the carline to the side plates of the car.

In the accompanying drawings, which illustrate one form of carline made in accordance with my invention, Figure 1 is a vertical section on a reduced scale of the roof of the car to which my carline is applied, the filling block being omitted; Fig. 2 is a section taken on the line 2—2 of Fig. 1; Fig. 3 is a section taken on the line 3—3 of Fig. 1; and Fig. 4 is a top plan view of one end of the carline and the side plate of the car to which the same is secured.

Like marks of reference refer to similar parts in the several views of the drawings.

The carline consists of a tie beam 5, a truss beam 6, and a strut 7. The ends of the carline are secured to the side plates 8 of the car. Each of the beams 5 and 6 is formed of angle iron, the horizontal webs of the two beams being brought into the same plane at the end of the carline so that both of said horizontal webs will bear upon the top of the side plate 8. The ends of the two beams are secured together by means of rivets 9. In order to secure the carline to the side plates 8, the horizontal flanges of the members 5 and 6 are separated from the vertical flanges for a distance from the ends and the two parts are spread so as to form members 10 and 11 respectively which are

secured to the side plates 8 by means of bolts 12. Secured in the truss beam 6 is a filling block 13, shown in Fig. 3. This filling block may be secured to the beam 6 by means of a bolt 14 or in any other suitable manner. Resting upon the filling block 13 are the purlins 15 supporting the inner roof 16. Above the purlins are the roof strips 17 upon which are placed roof boards 18. 19 is the ridge pole of the car. It will be noted that the lower face of this ridge pole 19 is somewhat above the line passing through the lower faces of the purlins 15. In order to secure a support for the ridge pole 19, the strut 7 is extended somewhat above the truss beam 6 and is provided with a turned over portion 20 which forms a seat for the ridge pole. 70 This portion 20 can be made of sufficient size to form an effective seat for the ridge pole. Formed in this seat 20 are a pair of holes 21 through which pass bolts 22 securing the ridge pole in position on the seat 20. 75

It will be evident that by the use of the extended strut, I am able not only to form a seat for the ridge pole when the same is out of alinement with the lower face of the carline, but I am also enabled to secure a seat of 80 sufficient extent to properly support the pole and to provide means for securing the ridge pole to the seat without weakening the truss beam of the carline.

Having fully described my invention, what I claim as new and desire to secure by Letters Patent of the United States is:

1. A carline comprising a tie beam, and a truss beam, said tie beam being formed of angle iron, the end of said tie beam having 90 its horizontal flange separated from its vertical flange and spread to form a fastening member.

2. A carline comprising a tie beam, and a truss beam, both of said beams being formed of angle iron, the ends of said beams having their horizontal flanges separated from their vertical flanges and spread to form fastening members. 95

In testimony whereof, I have hereunto set 100 my hand and affixed my seal in the presence of the two subscribing witnesses.

LOUIS A. HOERR. [L. S.]
